UNITED STATES PATENT OFFICE

FRED W. CHIPMAN, OF FRAMINGHAM, MASSACHUSETTS

STEAM BOILER

Application filed June 15, 1929. Serial No. 371,285.

This invention relates to boilers for generating steam and has for its general object to provide a boiler which will produce a maximum yield of steam per square foot of 5 radiating surface.

The object of the invention is further to provide a boiler in which the natural circulation or convection of water within the boiler is artificially accelerated.

10 The object of the invention is further to provide a means within the boiler connected with the feed water system which will prevent excessive temperatures at the hot areas of the radiating surfaces.

15 The object of the invention is further to provide a means to distribute the relatively cool feed water rapidly as it enters the boiler over a wide area.

Other objects and features will more fully 20 appear from the following description in connection with the accompanying drawings and will be particularly pointed out in the claims.

In the drawings:

25 Fig. 1 is a longitudinal cross section through the boiler.

Fig. 2 is a transverse section through the front water leg of the boiler showing the feed water system.

30 In order to maintain a high degree of efficiency a boiler must be so designed that a free natural flow of water may take place within the boiler from the region of higher temperature to the regions of lower temperature. The rapidity with which such circulation takes place determines to a large extent the capacity of the boiler to generate steam. If a body of water, for instance, that in contact with the region of high temperature of 35 the radiating surface, becomes heated to the boiling point and is retarded in its natural tendency to rise, the proper function of the boiler is greatly impaired. If on the other hand this body of water is moved automatically in some manner cooler water will take 40 its place and a more rapid heat transference from the radiating surfaces to the water will result. If such a relatively rapid circulation is maintained the total volume of water 45 within the boiler is being vaporized at a

greater rate which results in a greater capacity to generate steam. Furthermore much higher fire box temperatures may be maintained even to the point of using high pressure forced draught in which case the areas 55 of the boiler shell receiving direct contact of the flame from the fire are cooled to a safe temperature. In other words the rapid circulation of water within the boiler will prevent burning of the hot spots. 60

The principles of the invention may be adapted to substantially any type of boiler. The type herein shown is commonly known as a "Scotch boiler" which is one form of horizontal return tubular construction. In 65 this type of boiler the circulation takes place from the rear thereof which is the hottest region upwardly and then passes forwardly to the front and thence down. The boiler is generally of standard construction having 70 a main shell 1 having a front plate 2 and a rear plate 3. Within the lower part of the main shell 1 are located fire box shells 4. The number of the shells is immaterial and forms 75 no part of the invention. Within the shells 4 are grates to support the combustible material in whatever form it is used. It is not essential however that a grate be used since any means of firing the boiler may be employed such as oil or gas. 80

The shells 4 open into the lower end of a combustion chamber 5. The front wall of the combustion chamber forms the rear tube sheet 6 while the rear wall thereof is secured to the rear plate 3 in any desirable manner 85 as by stay-bolts 7. Fire tubes 8 are secured at one end in the rear tube sheet 6 and extend horizontally toward the front and are secured in the front plate 2 which constitutes the front tube sheet. The products of 90 combustion pass from the fire box through the rear of the fire box shells 4 into the lower portion of the combustion chamber 5 and thence upwardly and into the fire tubes 8 and out the forward end of the boiler to a 95 smoke box 9 which leads to a stack not shown.

Above the boiler is located a horizontal steam and water drum 10 which is connected thereto by water legs 11 and 12 located near the front and rear of the boiler. The tem- 100

perature of the water at the rear of the boiler is considerably higher than that at the front of the boiler. As a consequence of this the circulation of water therein is upwardly through the rear water leg 12 and thence forwardly through the drum 10 and down through the water leg 11 to the front end of the boiler.

The present invention resides in providing means to increase the natural tendency of the water to follow the path above described. To do this the feed water pipe is led into the water drum at the point 13 and extends forwardly to a point within the front water leg 11 and then vertically downward to a point within and adjacent to the shell 1 of the main boiler. At this point the feed water pipe preferably is led for a short distance in a substantially horizontal plane at right angles to the longitudinal axis of the boiler. This may be done by bending the pipe into a horizontal position at its end or the end of the pipe may be fitted with a T 14 which ejects the feed water in opposite directions against the cylindrical sides of the main boiler shell.

If desired the T 14 may be fitted with leaders such as sections of pipe 15 which effectively direct the feed water which is introduced under pressure in more definite paths in proximity to the boiler shell.

By leading the feed water pipe downwardly through the front water leg the heat absorbed by the feed water as it passes through this portion of the pipe lowers the temperature of the water passing downwardly through said water leg and consequently accelerates the downward circulation thereof. Furthermore the heat thus transmitted to the feed water raises its temperature before it emerges from the feed water pipe into the boiler thereby further increasing the efficiency of the boiler.

By means of this construction the cooler incoming water is directed down the sides of the boiler to a point at the lower cooler portions thereof. It is desirable however to direct the water flowing downwardly through the water leg 11 to the bottom of the boiler in a more positive manner. To do this a chamber or conduit of comparatively small area extends downwardly along both sides of the main shell 1 and is open at the bottom of the boiler. This chamber or conduit directs the flow of water to a point below the fire box. This conduit is formed by a partition wall 16 which extends from the front plate 2 rearwardly to a point beyond the water leg 11. The partition wall 16 is brought downwardly a short distance from and parallel to the main shell 1 and is stopped at a point near the bottom of the boiler.

The flow of water downwardly from the leg 11 by reason of its contact with the partition

wall 16 will be divided and substantially one half the flow will pass down one side and the other half down the other side emerging from the conduit at the cool lower region of the front end of the boiler. As a result of this structure the down flow of the water through the leg 11 is met by a relatively small body of water having a small inertia. The force of the flow of water down the leg 11 thus being confined to this relatively small body of water is able to move it at a rapid rate.

The present invention is readily adapted to be used in connection with this special conduit construction although it is not confined to use in boilers thus equipped. By means of the specially formed feed water outlets which are located within the conduit the flow of water is greatly accelerated. Both the impact of the feed water as it is forcibly ejected from the outlets and also the ejector effect upon the water adjacent the outlet combine to intensify the flow within the conduits thus increasing the general circulation within the boiler.

Having thus described the invention, what is claimed as new, and desired to be secured by Letters Patent, is:

1. An internally fired boiler comprising a main cylindrical shell having front and rear tube sheets, fire tubes connecting said tube sheets, a fire box shell within the main shell extending between said tube sheets, a combustion chamber communicating with the rear end of said fire box shell and said fire tubes, a smoke box communicating with the tubes at the front end of the boiler, a horizontal water and steam drum above the boiler, water legs connecting the main shell and the drum at points near the front and rear thereof, a partition wall at the front of the boiler spaced a short distance from said main cylindrical shell and extending part way of the length of the shell to form a circulating conduit extending from the front water leg downwardly along both sides of the main shell and opening at the bottom, a feed water pipe having leaders extending in opposite directions from its end into said conduit to project the feed water into the said conduit in directions to accelerate the flow of water downwardly therein.

2. A tubular boiler comprising a main cylindrical shell having front and rear tube sheets, a fire box, a combustion chamber communicating therewith, fire tubes connecting the tube sheets and communicating with said combustion chamber at one end and a stack at their other end, a water and steam drum above the boiler, water legs connecting the boiler shell and drum, one of said legs being situated adjacent the rear of the boiler to conduct the rising convection currents and one adjacent the front of the boiler to conduct the downward currents, a partition wall at

the front of the boiler spaced a short distance from the cylindrical shell to form a conduit extending from the front water leg downwardly along both sides of the boiler shell and opening at the bottom, and means to project the feed water downwardly and laterally into said conduit at the upper portion thereof to accelerate the downward currents:

5 In testimony whereof, I have signed my name to this specification.
